(57) **CLAIM**

The ornamental design for a dental light, as shown and described.

DESCRIPTION

FIG. 1 is a front, left, top perspective view of a dental light, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view of the enlarged scale thereof;

FIG. 8 is a bottom plan view of the enlarged scale thereof;

FIG. 9 is an enlarged view of detail 9 in FIG. 1;

FIG. 10 is an enlarged view of detail 10 in FIG. 1; and,

FIG. 11 is a front, left, top perspective view of the dental light in a detached state.

The dashed broken lines in the figures are for the purposes of illustrating portions of the dental light and form no part of the claimed design.

The dash-dot-dash broken lines are for notating enlarged views and form no part of the claimed design.
